CONTROL HANDLE FOR CAR WINDOWS

William A. Berg, Yakima, Wash.

Application December 30, 1935, Serial No. 56,746

5 Claims. (Cl. 74—547)

This invention relates to rotary control handles and particularly is directed to improved mechanism for raising and lowering the windows of automobiles or other vehicles, the object, generally stated, being to provide an improved handle which, when not in use, may be recessed within the door to eliminate interference with the vehicle occupants, which provides a symmetrical design of the fitting to render the same more attractive, and which generally is more advantageous than the rigid crank-arm arrangements conventionally employed.

The invention consists in the novel construction, adaptation, and combination of parts hereinafter described and claimed, the preferred embodiment being illustrated in the accompanying drawing, wherein:

Figure 1 is an elevational view representing the invention as applied to an automobile door.

Fig. 2 is an enlarged plan view of the invention; and

Fig. 3 is a transverse vertical section taken on the line 3—3 of Fig. 2.

Particularly as respects the drawing, the reference numeral 5 represents an automobile door provided with a window 6 supported for vertical movement by means of well-known or suitable lever or gear mechanism which, as indicated, includes a shaft 7 supported for rotary movement 30 and protruding from the inner side of the door.

According to the present invention, the fixed-angle crank-arm conventionally utilized to impart rotary movement to said shaft is replaced by a member 10 of a relative disk shape formed with a central socket arranged to fit over a squared extension 8 of the shaft 7, a screw 11 securing the same. Provided by said disk member is a radial cavity 12 the function of which is to house a handle 13 to normally locate the latter in a recessed position flush or nearly so as respects the surface of the disk member, said handle being pivotally mounted by means of a pin 14 carried by the disk member at the outer limits of the cavity. The handle, as represented by full and dotted lines in Fig. 3, is adapted for movement from normal recessed to an exposed position lying at right angles to the plane of movement of the disk member, and for yieldably maintaining the handle in either of said selected positions, the hub 15 of the handle desirably is formed with planed surfaces 15' disposed to engage a fixed spring 16 secured to the floor of the cavity. Any suitable spring, replacing the fixed spring 16, might as readily be used in modifying the construction where it is desired to auto-

matically return the handle to recessed position following use of the same. The cavity 12, as indicated, is somewhat of a pear-shape to form finger recesses laterally of the handle in facilitating the withdrawal of the handle to its crank-forming position.

To afford an open chamber within which the disk member is rotatably received, I provide a plate element 17 which preferably is designed to fit an annular recess 18 formed in the inner wall 10 of the vehicle door, the plate element about its perimeter having a trim-forming flange 19 which operates to cover the edges of velour or other upholstery 9 employed in surfacing the door.

The invention should be clear in its provision 15 of a window-control arrangement which, when not in use, lies flush with the surface of the door in a manner to prevent the same from interfering with the driver or other occupant of the vehicle either when entering and leaving the vehicle or 20 while riding in the same.

Modifications of the invention will readily appear and it is my intention that the invention shall be limited only as by expressed restrictions in the hereto annexed claims.

What I claim, is:—

1. In combination, a rotary spindle, a wall structure through which said spindle extends formed with an exposed cylindrical chamber lying in concentric relation to the spindle, a disk, 30 operatively engaging the spindle for rotating the latter, revolvably received in the wall chamber and formed in its exposed surface with a recessed cavity which lies in radial relation to the disk to locate the same between the center and the perimeter of the disk, and a crank handle for operating the disk pivotally received in the disk recess with its pivotal axis outermost for movement from an inoperative position within the cavity to an exposed operating position approximately at right angles thereto.

2. The structure defined in claim 1 wherein the disk is of single-thickness sheet metal construction peripherally provided with a reinforcing flange.

3. A control crank for a rotary spindle comprising the combination of a disk member having a central socket arranged to operatively engage the spindle and formed to provide a relatively pear-shaped cavity in the exposed surface of the same disposed radially of the disk to locate the cavity between the center and the perimeter of the disk, a handle-supporting shank pivotally received in said cavity for movement from a normal recessed position relatively flush with the 55

disk surface to an upstanding position relatively at right angles to the plane of movement of the disk, and a handle-forming member sleeved over the shank for relative rotary movement, the pivoted hub of said shank lying in the restricted throat of the cavity and toward the perimeter of the disk whereby the sleeve lies in the greater expanded portion of the cavity and toward the disk center, said expanded portion of the cavity being of a width to permit the introduction of the fingers of the operator at each side of the sleeved handle for withdrawing the handle from the cavity.

4. In combination with a rotary spindle having its end projecting from a wall structure into a recess formed therein, crank mechanism for the spindle comprising a disk member revolvably received in the wall recess to lie in flush relation to the surface of the wall, and a cranking arm pivotally carried by the disk member for move-

ment from a normal recessed position at which the same lies flush with the disk member and with the surface of the wall to an exposed operating position at which the arm extends in parallel relation to the axis of the disk member from the perimeter of the latter, the length of said arm being less than the radius of the disk.

5. Crank mechanism for a rotary spindle comprising a single-thickness sheet metal disk stamped to provide a central socket by which the same is fitted over the spindle and a recessed cavity lying between the spindle-fitting hub and the perimeter of the disk, and a cranking arm normally disposed to lie in recessed relation to the disk within the cavity and pivotally coupled to the disk for movement from its recessed position into an exposed operating position at which the arm extends in parallel relation to the axis of the disk from the perimeter of the latter.
